UNITED STATES PATENT OFFICE.

WILLIAM STITT OVER, OF CALLENSBURG, PENNSYLVANIA.

APPARATUS FOR MAKING SPRINGS.

SPECIFICATION forming part of Letters Patent No. 390,892, dated October 9, 1888.

Application filed February 3, 1888. Serial No. 262,905. (No model.)

To all whom it may concern:

Be it known that I, WILLIAM STITT OVER, a citizen of the United States, residing at Callensburg, in the county of Clarion and State of Pennsylvania, have invented certain new and useful Improvements in Apparatus for Making Springs; and I do declare the following to be a full, clear, and exact description of the invention, such as will enable others skilled in the art to which it appertains to make and use the same.

This invention has relation to machines for manufacturing bed-springs; and it has for its object to form a durable spring, which may be securely attached to a slat without the employment of fastening devices, as commonly used for such purposes, and one which may be quickly made without great care or experience.

The invention will be fully understood from the following description and claims, when taken in connection with the accompanying drawings, in which—

Figure 1 is a view of two springs made by my improved machine, showing the same attached to a slat; and Fig. 2 is a cross-sectional view of a portion of a slat, showing a spring in position. Fig. 3 is a view of my improved machine in an operative position, and Fig. 4 is a view of the eye-forming device. Fig. 5 is a view of the mandrel with the spring partly formed on it, and Fig. 6 is a view of the eye-forming device with a spring engaged thereby in a manner to form the eye.

Referring by letter to the said drawings, A indicates a standard or vertical frame, which may be secured to a work-bench or in a vise to properly hold it in an upright position. This standard has apertures at its upper end, and is designed to receive, interchangeably, the cone or mandrel shaft and the eye-forming shaft.

B indicates the cone or mandrel, which is in outline of the form usually employed in the manufacture of bed-springs, and may be made of wood or other suitable material externally grooved, as shown. This cone is secured to a longitudinal shaft, C, which is of a sufficient length to receive its bearings in the upper end of the upright or standard A, and has its free end adapted to receive a crank-handle, as

shown, whereby the said shaft and its cone may be rotated. By having the crank-handle removable, as shown, it will be seen that after the wire has been turned on the cone its shaft 55 may be slipped out from the standard and the eye-forming shaft placed therein, as will be hereinafter more fully described. At the large end of this cone is secured an arm, D, which has its outer end hooked and extended beyond 60 the periphery of the cone and overlying the groove *a* at the starting-point thereof, as shown more fully in Fig. 3 of the drawings. This hook is designed to receive and hold one end 65 of the wire during the operation of forming the coils. The groove *b*, which forms the second coil of the spring, is provided, in advance of the hook E, with a point or elevation, F, which, although not entirely filling the said groove transversely, is sufficiently raised to 70 indent or mark the spring at the point where the eye is to be subsequently formed. The cone is protected at its reduced end with a stout metal tip, G, which also has external grooves to form the smaller coils of the spring, 75 and the shaft for the cone is extended, as shown at H, to form the closely-wound coils at the lower end of the spring.

The eye forming shaft K is of a diameter equal to that of the cone shaft, having a collar near its outer end to form a stop, and terminating in a forked portion, L, one branch of which is shown longer than the other to more readily set itself in the notch of the wire and bend the same.

The operation is as follows: A reel of wire being placed in proper position and the standard secured upright, as before described, the mandrel or cone shaft is placed in the bearings at the upper end of the standard and the crank-arm placed on the inner end thereof. The operator then grasps the wire and places the end under the hook E and bends the same on the said hook, so as to form a hook in the wire to enter the eye therein, as more fully 95 shown in Fig. 2 of the drawings. The shaft is then turned, when the wire will take the course of the groove until it reaches the point F, where a bend will be formed to indicate the point at which the eye M of the spring is to 100 be made. The operation is then continued until the spring has been formed, after which

the wire may be cut by a file or other suitable device. The spring thus formed is then removed and the cone-shaft slipped from the standard, after which the shaft K is placed 5 therein and the crank-arm applied. The fork of this shaft engages the wire at the point or bend marked by the cone, and by simply giving the shaft a turn while the spring is held in the other hand an eye—such as M—will be 10 formed therein to receive the hook on the free end of the wire.

It will be observed that the eye is formed in 15 the spring by coiling the wire around the long branch of the fork on the shaft K, the short branch serving as a means to hold the wire while the eye is being formed, and, being short, will hold the wire only during one rotation of the shaft.

In using my spring on slats it is simply necessary to form a hole in the slats of a diameter equal to the diameter of the reduced portion of the spring and force the same therein, when a firm attachment will be had without the use of objectionable devices.

Having described my invention, what I claim 25 is—

1. The combination, with a rotative shaft, of a cone or mandrel fixed thereon and grooved as described and the elevation in the groove of the cone to mark the wire at the point to 30 form the eye, substantially as specified.

2. The combination, with a standard, of a cone grooved as described, and having a shaft, and provided in one of the grooves with a marking elevation, and a rotative shaft having 35 one end forked to engage the wire at the point marked and form the eye therein, substantially as specified.

3. The combination, with the cone grooved as described and having a shaft, of the hooked 40 arm at the large end thereof and overlying the first groove and the elevation arranged in the cone to indicate the point to form the eye, substantially as specified.

In testimony whereof I affix my signature in 45 presence of two witnesses.

WILLIAM STITT OVER.
